UNITED STATES PATENT OFFICE.

FRANK H. THOMPSON, OF HOPEDALE, MASSACHUSETTS, ASSIGNOR TO DRAPER COMPANY, OF HOPEDALE, MASSACHUSETTS, A CORPORATION OF MAINE.

BRAKE MECHANISM FOR LOOMS.

No. 895,058.

Specification of Letters Patent.

Patented Aug. 4, 1908.

Application filed October 22, 1907. Serial No. 398,609.

To all whom it may concern:

Be it known that I, FRANK H. THOMPSON, a citizen of the United States, and resident of Hopedale, county of Worcester, State of Massachusetts, have invented an Improvement in Brake Mechanism for Looms, of which the following description, in connection with the accompanying drawing, is a specification, like letters on the drawing representing like parts.

This invention has for its object the improvement of the brake mechanism of a loom whereby a cause of breakage is removed and a better and smoother operation of the loom secured.

Loom brake mechanism usually comprises a rotatable member secured to the crank-shaft, and a pivotally mounted shoe to co-operate with the rotatable member, the means to effect the actuation of the brake mechanism operating quickly and sharply, whether automatically, due to a fault in the operation of the loom, or when the shipper is released by hand. A connecting link is interposed between such means and the shoe, the rear end of the link having a socket to receive a lug extended laterally from the shoe, and at times the sudden shock and strain due to the application of the brake mechanism will fracture the shoe or break off the lug.

The means to effect the actuation of the brake mechanism includes a frog with which the link is connected, and hence such frog is stopped sharply and at a fixed point immediately upon the engagement of the rotating member and the brake shoe.

If the loom is equipped with a so-called "dead" frog at the opposite side it can move forward a little further when the loom bangs off, as a rubber cushion is interposed between the dead frog and the abutment on the loom frame, so that there is a slight inequality in the movement of the two frogs at the time of bang-off, tending to twist the lay.

In my present invention I provide a slight yielding or cushioning action between the link and the brake shoe, so that the severe shock and strain thereupon is eliminated and when live and dead frogs are used the movement thereof is equalized by the cushioning action so that there is no tendency to twist the lay, the movement at each end thereof being the same.

The novel features of my invention will be fully described in the subjoined specification

and particularly pointed out in the following claims.

Figure 1 is a left hand side elevation of a sufficient portion of a loom, with my invention applied thereto; Fig. 2 is a detail, partly in section, showing the yielding or cushioned connection between the brake shoe and the connecting or transmitting link.

The driving or crank-shaft 3, the lay A³ having the dagger d of the protection mechanism, to co-operate with the live frog F, the annular rotatable brake member 4 fast on the crank-shaft, the co-operating shoe 5 pivotally mounted at 6 on the loom-side, the shipper 7 adapted to be released by hand or automatically by the faulty operation of the loom, and the link 8 having a lost-motion connection with the frog and provided with a lug 9, may be and are all of usual or well known construction.

When the protection mechanism operates the movement of the frog F actuates the link 8 to effect the operation of the brake-mechanism, and through the weighted arm 10, pivoted at 11 and actuated through release of the shipper, the link is moved to operate the brake mechanism, all in well known manner, the arm 10 having a toe 12 to co-operate with the lug 9 on the link.

In accordance with my present invention the rear end of the link is screwed into the shank 13 of a housing 14, see Fig. 2, having an opening in its side to receive a lug 15 extended laterally from the brake shoe 5, the housing being of sufficient length to receive a yielding or cushioning block 16 of rubber, preferably interposed between the rear end 17 of the housing and the lug 15.

When the link is moved in the direction of the arrow 25, it will be seen that the motion is transmitted to the lug 15 through the yielding member 16, so that undue shock and strain upon the lug or the brake shoe is taken up or absorbed, obviating the tendency to breakage when two metal parts come directly together with no opportunity for yielding. By this yielding or cushioned connection between the link and the brake shoe I have eliminated breakage of the shoe or its lug, and have also rendered the operation of the brake mechanism smoother and less violent in its effects upon other parts of the loom.

When the loom is provided with live and dead frogs the invention is of value, for when

the loom bangs off and the cushioned dead frog permits slight forward movement of the lay at that side the momentum of the lay will also act through the live frog F and the connecting link, at the opposite side, to compress the cushion 16, so that the two ends of the lay will have a slight forward movement in unison before stopping at front center. This obviates any twisting tendency of the lay, which would occur if the lay were positively held by the link 8 at the live frog end and permitted to move forward slightly at the opposite end, where the dead frog is located.

Having fully described my invention, what I claim as new and desire to secure by Letters Patent is:—

1. In a loom, brake mechanism comprising a rotatable brake member and a shoe to cooperate therewith, means to effect the actuation of the brake mechanism, a link connected at one end with said means, and adjacent the shoe at its other end, a housing on one of said parts, and a lateral lug on the other part entering the housing, and a yielding member inserted in the housing between the lug and the end of the housing to take up shock when the brake mechanism is operated.

2. In a loom, brake mechanism including a rotatable member and a shoe movable toward and from it, actuating means for the brake mechanism, a link connected at one end with said means and having a housing at its other end, a lateral lug on the brake shoe, to enter the housing, and a cushioning member inserted in the housing between the rear end thereof and the lug, to take up shock when the brake mechanism is actuated.

3. In a loom, brake mechanism including a rotatable member and a shoe to coöperate therewith, actuating means operative upon a fault in the operation of the loom, a link connected at one end with the said means and having a housing at its other end, a lateral lug on the shoe, entering the housing and a block of rubber inserted in the housing between its rear end and the back of the lug, to be compressed and thereby relieve the latter from shock when the brake mechanism is actuated.

In testimony whereof, I have signed my name to this specification, in the presence of two subscribing witnesses.

FRANK H. THOMPSON.
